INDICATOR LOCK

Filed July 15, 1927

UNITED STATES PATENT OFFICE

JOHN GARLINGTON RAMEY, OF ROME, GEORGIA

INDICATOR LOCK

Application filed July 15, 1927. Serial No. 206,037.

This invention relates to improvements in indicating locks, as described in the following specification and illustrated in the accompanying drawings that form part of the same.

5 The invention consists essentially in the novel construction and arrangement of parts, whereby a series of sliding plates or tumblers having on their respective ends characters or numbers denoting the key actuating them, 10 are held locked in position with the numbers visible through a window in the lock casing, by means of a resetting plate which can be released only by the master key.

Particular objects of this invention are to 15 obtain a positive indication of the party last operating the lock, and to devise an indicating lock of simple and durable construction, without the use of a recording tape.

A still further and important object of this 20 invention is to devise a lock that indicates the last key that operates it, and one that must be reset by the master key after each operation, before any further operations are possible.

With the above and further objects in view 25 the invention will be clearly understood from a perusal of the following description taken in connection with the accompanying drawings and forming part of this application, and wherein—

30 Figure 1 is a perspective view of an indicating lock constructed in accordance with the invention and showing the cover removed.

Figure 2 is a view showing both cover and 35 reset plate removed, and showing the sliding plate in locked or registering position.

Figure 3 is a view showing the plate 20 and cooperative parts.

Figure 4 is an elevational view of the keys for actuating the mechanism.

40 Figure 5 is a detail perspective view, showing ends of the tumblers with identifying marks displayed thereon.

Like numerals of reference indicate corresponding parts in each figure.

45 Referring to the drawings, 1 is the lock casing here shown in the form of a padlock, though it must be understood that the invention may, with slight changes, be adapted for other well-known types of locks. 2, 3, 4, 6, 7, 50 are pins rigidly secured in the back of the

casing 1 and projecting inwardly therefrom. 5, 8, 9 are pins with reinforcing shoulders 30, 31, 29, rigidly secured in the back of the casing 1 and projecting inwardly therefrom. 10 is a pin rigidly secured in the back of the casing 1 and projecting inwardly therefrom and about which the shackle 13 pivots. 11 is a reset plate, pivoted on pin 3, with an arm 12 perpendicular to its surface which rests in slots 57 when the tumblers 14 are in an indicating position and in slots 58 when the tumblers are not, and with a finger 28 actuated by a bit 50 on the master key A. 14 is a plurality of tumblers having the slots 25 and 32 through which the pins 2 and 3 extend respectively, said tumblers being slidable thereon. 15 is an opening or window in the casing 1 through which the indicating marks or numerals on the extremities of the extensions 16, 17 and 18 of the tumblers 14 are readable when said tumblers are in a locked position. 19 is a ledge on the end of a shackle; said end may extend through a slot 36 in the casing 1, so as to allow ledge 19 to engage in a notch 21 in shackle plate 20. 26 is a spring secured at one end to the pawl 34 and having its other end extending into the notch 37 in the plate 20, said spring actuating said pawl and plate on their respective pivots 2 and 6. 22 is a spring engaging the reset plate 11 in the notch 38 and extending part way around the pin 6 and bearing at its opposite end against a stop 24 formed on the inner wall of the casing 1, said spring actuating and holding the reset plate 11 with arm 12 bearing against the tumblers 14. The protruding finger 59 on shackle plate 20 engages arm 12 of reset plate 11 and elevates it to release the tumblers 14. 23 are springs engaging the tumblers 14 in side slots 39 thereof and extending part way around the pin 6 and bearing at their opposite ends against the stop 24 formed on the inner wall of the casing 1, said spring actuating the sliding tumblers 14. 27, are fingers 90 projecting from the tumblers 14 and extending adjacent to the pin 7; said fingers being adapted to engage respectively the bits 51, 52, and 53 of the keys B which are inserted over the pin 7; and cause the tumblers to move to the locked position shown by dotted lines of 100

Fig. 2. 35 is a collar on pin 3 which projects through the L-shaped slots in tumblers 14. 40 are protruding fingers on one extremity of the tumblers 14 and respectively engage the bits 54, 55 and 56, on keys B when any one of the tumblers is in an indicating position to prevent any further turning of the key.

With the shackle 13 locked in closed position, the hook 19 at the free end of the shackle 10 is in engagement with the notched part 21 of the plate 20, as shown in Figs. 2 and 3. By employing any one of the keys A or B the shackle can be released. When one of the keys is inserted in the lock with its barrel over 15 the pin 7 and is turned in the proper direction, the bit 60 at the inner end of the key engages the plate 20 and the latter is turned on its pivot 6 toward the right from the position shown in Fig. 3. This movement of the 20 plate releases the shackle and imparts a thrust to the spring 26 that turns the pawl 34 to project the free end of shackle upward from the casing. The released plate 20 and the pawl 34 are moved into mutual engagement 25 to be held thereby in a position preliminary to subsequent engagement between the plate and the hooked end of the shackle thrust into the casing.

In the normal position of the parts when 30 the shackle is locked, the tumblers 14 are positioned to the left on the pins 2 and 3, being normally pressed to that position by the springs 23, as shown in Figs. 1 and 2. In this position of the tumblers, the arm 12 35 of the reset plate 11 registers with the alined notches 58 in the upper edges of the tumblers, the plate being normally pressed by the spring 22 to depress the arm. With the tumblers so positioned and held, their marked ends 16, 17, 18 are withdrawn and depressed from the window 15 of the casing. As shown in the drawings, there are three tumblers to coact with three auxiliary keys B. The relative arrangement of the bits 51, 52, 53 of the 40 respective auxiliary keys and of the fingers 27 of the respective tumblers is such that each auxiliary key can actuate only a particular tumbler.

When a particular auxiliary key B is employed to open the lock, its barrel is thrust over the post 7 and as the key is turned its bit 60 actuates the plate 20 to release the shackle. As the plate turns the finger or cam-lug 59 thereon rides beneath the arm 12 55 and lifts the latter clear of the notches 58, the resetting plate 11 turning on the post 3 against the action of the spring 22 accommodates the movement of the arm. As the key rotates the bit, 51 or 52 or 53, engages the finger 27 of the particular tumbler controlling that particular key, thereby moving the tumbler against the action of its spring 23 to the right from the position shown in Fig. 2. As the tumbler so moves, the stud 3 passes 60 along the longitudinal part of the angular 65

slot 32 and as it reaches the angle of the slot, the bit passing beneath the lower end of the finger 27 lifts the tumbler to the position indicated by the dotted line figure 33 in Fig. 2, with the post 3 engaging the lower end of the transverse part of the slot 32. When the tumbler moves as indicated, it rides beneath the previously raised arm 12 until the latter, through the action of spring 22 on the resetting plate 11, is forced into the notch 57 of the tumbler and the latter is held in the dotted line position. In this position, the marked end, 16 or 17 or 18, of the tumbler registers with the opening 15 in the casing. The mark, "1" or "2" or "3", designates the 70 particular tumbler that has been moved to register the mark and thereby indicates the particular key used for the purpose; the key may be identified by a peculiar mark (not shown) showing its association with the particular tumbler that has been moved. Complete rotation of the key is prevented by the arm 40 of the moved tumbler engaging the bit, 54 or 55 or 56, of the key so that further 75 operation of the tumbler is prevented and its 80 key-indicating position continues until the tumbler is reset.

When the master key A is used to reset a displaced tumbler, it is inserted in the lock over the post 7 and rotated in the required 85 direction. As the key is rotated its bit 50 engages the arm 28 of the resetting plate 11 and the latter is turned against the action of the spring 22 to lift the arm 12 from the notch 57 of the engaged tumbler. When this 90 occurs, the spring 23 of the released tumbler moves the latter to its initial position, reset for the next unlocking operation of the auxiliary key for that tumbler. When the plate 11 is released by the key, the arm 12 drops into the alined notches 57 and the lock is ready 95 for the next locking operation.

The construction and arrangement of parts as herein described is for a shackle lock, but the parts may be changed considerably to adapt the principle of the lock to other well known forms without departing from the spirit of the invention so long as the main feature is adhered to, that of a plurality of indicating tumblers, each adapted to be 100 moved by its specific key, and rendering the lock incapable of further operation until released by a master key. The other parts may be designated and arranged to accommodate 105 the working parts of the different styles of lock.

What I claim as my invention is:—

1. In an indicating lock, the combination with a casing, of a lock mechanism, a plurality of indicating tumblers adapted to be locked one at a time in an indicating position, a reset plate having an arm thereon to release the tumblers from locked position, springs one for each tumbler to return said tumblers 110

to normal position, and a spring for returning said reset plate to normal position.

2. In an indicating lock the combination with a casing, of a lock mechanism, a plurality of indicating tumblers having parallelly arranged oblong slots near one extremity and parallelly arranged L-shaped slots centrally located, and pins rigidly secured to the back of said casing and protruding inwardly through the said slots, said tumblers being movable on said pins, means to operate the tumblers to indicating position and means to reset the tumblers.

3. In an indicating lock, the combination with a casing, of a lock mechanism, a plurality of indicating tumblers, a pin secured in the back of said casing, a reset plate pivoted about said pin, and an arm extending perpendicularly from the face of said reset plate to engage the tumblers and hold them in their locked position.

4. In an indicating lock, the combination with a casing, a lock mechanism, a plurality of individual indicating means, means for operating the same, and means for moving said indicating means individually, both longitudinally and transversely for resetting the same after operation.

5. In an indicating lock, the combination with a casing, of a lock mechanism, a plurality of indicating tumblers each having a longitudinally extending slot and an angular slot therein, pins extending through said slots, means for actuating said lock mechanism and moving said indicating tumblers on said pins to indicating position, and means for actuating the lock mechanism and resetting the indicating tumblers.

6. In an indicating lock, the combination with a casing of a lock mechanism, a plurality of indicating tumblers, means for actuating said locking mechanism and moving said tumblers longitudinally then swinging them transversely into indicating position, and means for returning said tumblers to normal position.

In testimony whereof I affix my signature.
JOHN GARLINGTON RAMEY.
